ELECTRIC DISCHARGE LAMP AND STARTING DEVICE THEREFOR

Henry J. McCarthy, Danvers, Mass., assignor to
Hygrade Sylvania Corporation, Salem, Mass.,
a corporation of Massachusetts

Application November 8, 1939, Serial No. 303,397

2 Claims. (Cl. 176—124)

The present invention relates to electric gaseous discharge lamps, and in particular to such lamps having thermionic cathodes and to apparatus for starting and operating such lamps.

5 An object of the invention is to provide an electric gaseous discharge lamp with thermionic cathodes and with apparatus for allowing the cathodes to preheat for a definite interval before the discharge is started between them. A further object is to provide a switch with the proper time delay to allow preheating of the cathodes under all possible conditions of starting and restarting, and which will not have a deleterious time lag when put into operation for restarting a lamp. A further object is to provide a switch which will start the lamp without a sudden voltage surge.

20 A feature of the invention is a switch actuated by a bimetallic switch heated by a resistance unit connected between the electrodes of the lamp to be started. A further feature is the use of the difference between starting and operating voltages to allow the switch to be normally open, to close when voltage is applied to the lamp, and to again open after a predetermined cathode heating period to start the lamp.

25 Other objects, advantages and features of the invention will be apparent from the following description, taken in connection with the accompanying drawing, in which:

30 Figure 1 is a schematic diagram of the arrangement of apparatus according to the invention;

Figure 2 is a side view of the switching device according to the invention; and

35 Figure 3 is a cross-sectional view of part of the same device.

In Figure 1, a gaseous discharge lamp 1 has the glass envelope 2 with electrodes 3, 4 at each end. The glass envelope may have an internal coating 5 of fluorescent material, if desired, and the electrodes 3, 4 may be coils of tungsten wire coated with one or more of the alkaline earth oxides to increase the electron emission, with the auxiliary electrodes 6, 7 to aid in starting.

40 An atmosphere of inert gas, such as argon, and also a vapor, such as mercury, may be sealed into the envelope. A lead-in wire 8 from one end of one filament may be connected to one end of the power line from which the device is operated, an end of the other filament may be connected, through a suitable ballast impedance such as the inductance coil 10, to the other end of the power line by the connection 11. The remaining ends 11, 12 of each filament may be 45 connected together through the resistance 13.

A bimetallic strip is placed close enough to the resistance 13 to be heated by the passage of current therethrough, and is arranged to close the contacts 20, 16 when it is heated, thereby shortcircuiting the resistance 13 and allowing 5 it to cool.

Figures 2 and 3 show the arrangement of resistance and bimetallic strip in more detail. A graphite resistance rod 13 is held between the two lead-in strips 18 and 19. Near the middle 10 of the rod a bimetallic strip 20 is supported at one end 21 and bent around the carbon rod, being free at the other end 22, which when current is passed through the rod touches the contact 16. The strip 20 may be connected at its supported 15 end to the lead-in strip 18 and the contact 16 may be supported from, and electrically connected to, the other lead-in 19. The whole unit 20 may be sealed into a bulb 23 of metal, glass or the like, preferably filled with an inert gas. The lead-in strips 18 and 19 may be attached to the lead-in wires 24, 25, which pass through the bulb. If the latter is of metal the lead-in wires must, of course, be insulated from the metal.

25 In operation, when a voltage is placed between the wires 8 and 11, a current flows through the resistance 13, heating it, which in time heats the bimetallic strip 20 causing it to expand enough to meet contact 16. That short-circuits the resistance 13, allowing the latter and strip to cool. 30 In the meantime current passes through the filaments 3, 4, heating them. The resistance 13 and strip 20 are proportioned so that they cool enough to break the contacts between strip 20 and contact 16 at about the time the electrodes 3, 4 are 35 heated sufficiently to start the discharge. The contacts break, placing voltage between the electrodes 4 and 5 and starting the discharge. The resistance rod 13 should have a high resistance, say 50,000 ohms. For this resistance I 40 have for example used a graphite rod 0.45 inch long and 0.025 inch diameter.

45 In order for my circuit to work properly, the lamp must have a gas pressure and electrode spacing, and the tube diameter, such that, when the electrodes are cold, no substantial discharge will pass between the electrodes at the line voltage used. At the instant of connecting my device to the line, then, no discharge will occur in the lamp but current will pass through the resistance 13. This resistance should be high compared to the impedance of the reactance or inductance coil so that practically the entire line voltage will appear across the resistance 13. The 50 passage of the current through the resistance 55

should be enough to heat the latter sufficiently to transfer enough heat to the bimetallic strip 20 to expand the latter enough to close the contacts, 15, 16. The small current passed through the filament during the period will not be sufficient to heat it appreciably, so the interval between the connecting of the switch to the line and the closing of the contacts may well be made short. However, the period between the closing of the contacts 20, 16 and the opening of them when the strip 20 has cooled sufficiently to open them must be made long enough, generally at least half a second, to allow the filaments 4, 5 to reach the proper electron-emitting temperature.

15 It will be noted that, on connecting the circuit to the line, no discharge will at first pass between the electrodes in the tube, and practically the entire line voltage will be impressed across resistance 13, heating it and causing the bimetallic strip 20 to close the contacts 15, 16. Closing these contacts short-circuits the resistance, causing it and the bimetallic strip to cool. When they have cooled sufficiently the contacts will 25 open; and the period in which they remain closed should be adjusted so that the filaments heat up to their proper electron-emitting temperature during that period. Then when the contacts open the discharge will start in the lamp between the heated electrodes.

30 The resistance 13 will again be connected across a voltage, the drop across the lamp, and one might think that it would again heat up and go through its cycle, giving a flashing lamp instead of a smoothly operating one. Such, indeed, might be the case. But in the present invention we take advantage of the fact that the voltage drop across the lamp after starting is less than the drop across the lamp prior to 35 starting. We design the resistance 13 so that with the full line voltage across it, it is heated enough to close the bimetallic contacts, but so that with the lower lamp operating voltage across it, it does not reach a high enough temperature 40 to close the contacts.

45 In one lamp with which I have used the device, for example, the line voltage was 220 and the lamp operating voltage was only 110 volts. There was thus only half the voltage across the 50 resistance after starting that there was before. This would mean that the resistance 13, if contact in value, would only take one-fourth the power while the lamp was operating that it took on starting. However, by using a graphite resistor, which has a negative temperature coeffi-

cient, the ratio can be made even less than one fourth.

5 In order not to unduly prolong the filament heating period beyond that necessary to reach the proper temperature, an inert gas around the carbon rod is useful to quickly cool the resistor when it is short-circuited. Making the rod of small diameter is also useful in that respect.

The best position for the bimetallic strip is, bent around the middle portion of the carbon 10 rod, since the middle of the rod is hotter than the ends when current flows.

15 It will be noted that the present switch when operated in my new circuit enables the lamp to be started easily without the damaging shock of a sudden voltage surge, as might be produced by a quick-acting switch of the magnetic or mercury type. If however, a magnetic type switch is desired for any reason it can be used in a manner similar to the present switch by 20 replacing the bimetallic strip by an armature capable of being attracted by the magnet. In such a case, the magnet coil replacing resistor 13 should have an impedance large compared with that of the impedance 10, and should be 25 such that the line voltage causes the switch to be closed, and yet the operating voltage of the lamp is not sufficient to close it.

What I claim is:

1. In combination: an electric gaseous discharge lamp having at least two electrodes, one at least of said electrodes being of the filamentary type; a ballast impedance in series with said lamp; a resistor connecting one end of a filamentary electrode to the other electrode, said 30 resistor having an impedance large compared with that of the ballast impedance; and a bimetallic strip in position to be distorted by the heat developed in said resistor when the latter passes current and to short-circuit said resistor 35 when distorted sufficiently.

2. The combination of claim 1 in which: the ballast impedance is such that the operating voltage of the lamp after the electrodes has been heated is much lower than the starting voltage 45 when the electrodes are cold; and in which the resistor connected between the lamp electrodes is positioned so that the heat produced in it by the operating voltage of the lamp is insufficient to distort the bimetallic strip enough to short- 50 circuit said resistor, but so that the voltage necessary for short-circuiting is nonetheless below the starting voltage of the lamp when the filamentary electrode is cold.
